US00D572494S

(12) **United States Design Patent**
Lowsky

(10) **Patent No.:** **US D572,494 S**
(45) **Date of Patent:** **** Jul. 8, 2008**

(54) **CHAIR**

(76) Inventor: **Jamie Lowsky**, 7000 Island Blvd., Apt. 106, Aventura, FL (US) 33160

(**) Term: **14 Years**

(21) Appl. No.: **29/279,118**

(22) Filed: **Apr. 19, 2007**

(51) **LOC (8) Cl.** **06-01**

(52) **U.S. Cl.** **D6/370**

(58) **Field of Classification Search** **D6/334-336, D6/369, 370, 371-373, 375-376, 379, 380, D6/381, 500-502; 297/411.43, 445.1, 446.1, 297/452.63, 452.64**

See application file for complete search history.
